UNITED STATES PATENT OFFICE.

EDMUND SHULTE AND JOSEPH WEITE, JR., OF YONKERS, NEW YORK.

DESIGN FOR A COMBINED CIGAR AND CIGARETTE STAND AND ASH-RECEIVER.

54,465.

Specification for Design.

Patented Feb. 10, 1920.

Application filed May 29, 1919. Serial No. 300,744. Term of patent 3½ years.

To all whom it may concern:

Be it known that we, EDMUND SHULTE, a citizen of the United States, residing in Yonkers, county of Westchester, and State of New York, and JOSEPH WEITE, Jr., a citizen of the United States, residing in Yonkers, county of Westchester, and State of New York, have invented a new, original, and ornamental Design for a Combined Cigar and Cigarette Stand and Ash-Receiver, of which the following is a specification, reference being had to the accompanying drawing, forming a part thereof.

In the drawings:—

Fig. 2 is a plan view.

We claim:—

The ornamental design for a combined cigar and cigarette stand and ash receiver as shown.

EDMUND SHULTE.
JOSEPH WEITE, JR.
